DRIVING LAMP CONTROL ARRANGEMENT

Jesse R. Hollins, Brooklyn, N.Y., assignor to Signal-Stat Corporation, Brooklyn, N.Y., a corporation of New York

Filed May 22, 1958, Ser. No. 737,153

10 Claims. (Cl. 340—81)

This invention relates to combined head lamp control and emergency signal switch and circuits for automotive vehicles and, more particularly, to novel switches and circuits including a pilot lamp burning steadily in the parking lamps on position of the control switch and flashing during emergency or "flare" operation of the switch.

Many drivers, due to inattention when driving on partly illuminated streets or roads, inadvertently drive with only their parking lamps lit, thus creating a hazardous condition for themselves, for other drivers, and for pedestrians. Also, drivers often turn on the parking lamps while driving in inclement weather, in fog and at dusk or dawn, and forget to turn off these lamps when leaving the vehicle, due to the lights being dim and not readily noticeable, thus unnecessarily discharging the battery. Accordingly, it would be desirable to have some means for indicating to a driver that he is driving with only his parking lamps on, when he should be using his headlamps.

In prior applications, I have shown and described vehicle lighting systems in which all the parking and tail lamps may be flashed simultaneously as an emergency warning signal or flare signal. In these arrangements, the switch controlling flare flashing of all the lamps has a flashing pilot or indicator lamp.

In accordance with the present invention, I combine the functions of driving or marker lamp control and of flare signal control in a single switch in such a manner that a pilot lamp common to both functions is steadily illuminated in the parking lamps on position, is flashed in the flare signal position, is extinguished in the "headlamps on" position, and is extinguished in the neutral or "off" position.

The novel combined control function switch has an off position and three on positions. In the first on position, the parking and tail lamps are steadily illuminated, and so is the pilot lamp. In the second on position, the headlamps and tail lamps are steadily illuminated, with selection between high beam and low beam being made by the usual foot operated selector switch, and the pilot lamp is extinguished. In the third on position, the parking and tail lamps are flashed as a flare signal and the pilot lamp is also flashed. The switch may be of the rotary type or may be of the pullout type.

By virtue of the pilot lamp being steadily energized only in the parking lamps on position and extinguished in the headlamps on position, there is no pilot dash light interference with a driver's vision when driving with the headlamps on.

For an understanding of the invention principles, reference is made to the following descriptions of typical embodiments thereof as illustrated in the accompanying drawing. In the drawing:

Fig. 1 is a schematic diagram illustrating the invention as incorporated in a vehicle lamp circuit controlled by a rotary switch; and

2

Fig. 2 is a similar diagram in which a pullout switch is used as the control switch.

Referring to Fig. 1, a combined headlamp and flare signal control switch 10 embodying the invention is illustrated as comprising a dielectric base 11, on which rotatably mounted is a circuit closer 15 having three arms 20, 25, and 30. Base 11 has fixedly mounted thereon three groups of contacts each cooperable with a different contact arm of circuit closer or switch operator 15.

Arm 20 is cooperable with contacts 21, 22 and 23, arm 25 is cooperable with contacts 26, 27 and 28, and arm 30 is cooperable with contacts 31, 32 and 33. The usual grounded vehicle battery 12, representing the vehicle source of electric potential, has its live terminal 13 connected to contacts 21 and 22. Contact 23 is connected by a conductor 14 to the grounded tail lamps TL.

Contacts 26 and 27 are connected to the dash lamps DL and, by conductors 16 and 14 to tail lamps TL. Contact 28 is connected to a dash or instrument panel mounted pilot lamp IL.

Contact 31 is connected to grounded parking lamps PL and also to pilot or indicator lamp IL. Contact 32 is connected to the common terminal of the usual foot operated selector switch FS having a pair of terminals respectively connected to the high beam and low beam filaments of grounded head lamps HL. Contact 33 is connected to one terminal of flasher FL whose other terminal is connected to battery 12.

Operator 15 is shown in the neutral or "off" position. When this operator is turned counterclockwise, its first position is the "parking lamps on" position in which arms 20, 25 and 30 respectively engage contacts 21, 26 and 31. The parking lamps, tail lamps, dash lamps, and pilot lamp IL are thus connected to battery 12 and steadily illuminated. Pilot lamp IL being illuminated, the operator is continually made visually aware that he is driving only his parking lamps on.

The next counterclockwise position of operator 15 is the "headlamps on" position. In this position, headlamp selector switch FS is connected to battery 12 through contact 22, switch arms 20 and 30, and contact 32. Pilot lamp IS is extinguished, because contacts 26 and 28 are not engaged by any switch arm. As pilot lamp IS is dark, it does not interfere with the driver's vision when he is driving with his headlamps on. The tail lamps TL remain energized through arm 25, contact 27, and conductors 16, 14.

In the third position of operator 15, arms 20, 25 and 30 are engaged, respectively, with contacts 23, 28 and 33. Thus, operator 15 is connected to battery 12 through flasher FL and arm 30. Parking lamps PL are flashed through arm 25 and contact 28, as is also pilot lamp IL. Tail lamps TL are flashed through arm 20 and contact 23. This is the emergency warning or "flare" signal position. It will be noted that a "flare" signal is also provided by turning operator 15 clockwise one position from the illustrated neutral position.

Fig. 2 illustrates the invention as incorporated in a push-pull type of control switch 110 comprising a base 11 on which is slidably mounted a conductive circuit closer 115 carrying contacts 120, 125, and 130. Slide contact 120 is selectively cooperable with base contacts 121, 122 and 123, slide contact 125 is selectively cooperable with base contacts 126, 127 and 128, and slide contact 130 is selectively cooperable with base contacts 131, 132 and 133.

Contacts 121, 122 are connected to live terminal 13 of grounded vehicle battery 12, and contact 123 is connected to flasher FL which is connected to battery terminal 13. Contacts 126, 127, 128 are connected to dash lamps DL and tail lamps TL. Contacts 131 and

133 are connected to parking lamps PL and pilot or indicator lamp IL. Contact 132 is connected to foot operated switch FS controlling selection of the high or low beams of headlamps HL.

Switch 10 is shown in the neutral position. When knob 135 is pulled to the first "on" position, slide contact 120 connects slide 115 to battery 12, dash lamps DL and tail lamps TL are steadily illuminated through contacts 125 and 126, and parking lamps PL and pilot lamp IL are steadily illuminated through contacts 130 and 131.

In the next pull position, slide 115 is again connected to battery through contacts 120 and 122. The dash and tail lamps are steadily illuminated through contacts 125 and 127, and switch FS is connected to battery 12 through contacts 130 and 132. Tail lamps TL and pilot lamps IL are extinguished as neither contact 131 nor contact 133 is connected to battery 12.

The third pull position is the "flare" position. Contact 120 engages contact 123 thus connecting slide 115 to battery 12 through flasher FL. Dash lamps DL and tail lamps TL are flashed through contacts 125 and 128, and parking lamps PL and pilot lamp IL are flashed through contacts 130 and 133. Headlamps HL are extinguished as switch FS is disconnected from slide 115.

The described system thus provides a vehicle lamp arrangement wherein a pilot lamp is steadily lit whenever the parking lamps are on, is extinguished when the head lamps are on, and is flashed in the "flare" position of the combined head lamp control and "flare" signalling switch.

While specific embodiments of the invention have been shown and described in detail to illustrate the application of the invention principles, it will be understood that the invention may be embodied otherwise without departing from such principles.

What is claimed is:

1. A driving lamp control arrangement for an automotive vehicle having a battery, head lamps, and parking lamps, said control arrangement comprising, in combination, a control switch having first and second input contacts connected to said battery and a third input contact, a first output contact connected to said parking lamps, a second output contact connected to said head lamps, a third output contact connected to said parking lamps, and a movable circuit closer having a neutral position, a first position interconnecting said first contacts, a second position interconnecting said second contacts, and a third position interconnecting said third contacts; a flasher connected between said battery and said third input contact; and a pilot lamp connected to said first and third output contacts in parallel with said parking lamps; whereby, in said first position said parking lamps and pilot lamp are steadily illuminated and said head lamps are extinguished, in said second position said head lamps are steadily illuminated and said parking and pilot lamps are extinguished, and in said third position said parking lamps and pilot lamps are flashed and said head lamps are extinguished.

2. A driving lamp control arrangement as claimed in claim 1 in which said circuit closer is rotatably mounted on a base carrying said contacts.

3. A driving lamp control arrangement as claimed in claim 1 in which said circuit closer is longitudinally slidably relative to a base carrying said contacts.

4. A driving lamp control arrangement for an automotive vehicle having a battery, head lamps, parking

lamps, and tail lamps, said control arrangement comprising, in combination a control switch having first and second input contacts connected to said battery and a third input contact, a first output contact connected to said parking lamps, a second output contact connected to said head lamps, a third output contact connected to said parking lamps, first, second, and third contacts connected to said tail lamps, and a movable circuit closer having a neutral position, a first position interconnecting said first contacts, a second position interconnecting said second contacts, and a third position interconnecting said third contacts; a flasher connected between said battery and said third input contact; and a pilot lamp connected to said first and third output contacts in parallel with said parking lamps; whereby, in said first position said parking lamps, tail lamps and pilot lamp are steadily illuminated and said head lamps are extinguished, in said second position said head lamps and tail lamps are steadily illuminated and said parking and pilot lamps are extinguished, and in said third position said parking lamps, tail lamps and pilot lamps are flashed and said head lamps are extinguished.

5. A combined head lamp control and flare signalling unit for automotive vehicles comprising, in combination, a control switch including a base having mounted thereon first, second and third input contacts and first, second and third output contacts, and a circuit closer movably mounted on said base and having a neutral position, a first position interconnecting said first contacts, a second position interconnecting said second contacts, and a third position interconnecting said third contacts; a flasher connected to said third input contact; and a pilot lamp connected to said first and third output contacts; whereby said pilot lamp is connected to said flasher in said third position.

6. A combined head lamp control and flare signalling unit for automotive vehicles as claimed in claim 5 in which said circuit closer is rotatably mounted on said base.

7. A combined head lamp control and flare signalling unit for automotive vehicles as claimed in claim 5 in which said circuit closer is longitudinally slidable relative to said base.

8. A combined head lamp control and flare signalling unit for automotive vehicles comprising, in combination, a control switch including a base having mounted thereon first, second and third input contacts, first, second and third output contacts, and first, second and third tail lamp contacts, and a circuit closer movably mounted on said base and having a neutral position, a first position interconnecting said first contacts, a second position interconnecting said second contacts, and a third position interconnecting said third contacts; a flasher connected to said third input contact; and a pilot lamp connected to said first and third output contacts; whereby said pilot lamp is connected to said flasher in said third position.

9. A combined head lamp control and flare signalling unit for automotive vehicles as claimed in claim 8 in which said circuit closer is rotatably mounted on said base.

10. A combined head lamp control and flare signalling unit for automotive vehicles as claimed in claim 8 in which said circuit closer is longitudinally slidable relative to said base.
